United States Patent Office.

JOSEPH P. ADAMS AND GEORGE HYDE, OF WHITNEY'S POINT, NEW YORK.

Design No. 4,732, dated March 28, 1871.

DESIGN FOR A STONE-DRAG.

The Schedule referred to in these Letters Patent and making part of the same.

To all whom it may concern:

Be it known that we, JOSEPH P. ADAMS and GEORGE HYDE, of Whitney's Point, in the county of Broome and in the State of New York, have invented a certain new and useful Design for Front of Stone-Boat; and do hereby declare that the following is a full, clear, and exact description thereof, reference being had to the accompanying drawing and to the letters of reference marked thereon making a part of this specification.

Our design is fully illustrated in the accompanying drawing; and

It consists in a curved casting, A, with countersunk holes, *a a*, along the lower edge and sides, as shown; also with a rectangular hole, B, through which the chain passes to draw the machine by.

This casting is designed for a fore-part of a stone-

boat or log-boat, which, being bolted to a straight plank, makes one of the usual shape, thereby saving the necessity of having plank sawed with a crook, as the iron makes the necessary curve in front; also prevents the wood from wearing out as soon as it would if made of wood alone.

What we claim is—

The design for front of stone-boat or log-boat, as herein shown and described.

In testimony that we claim the foregoing we have hereunto set our hands this 14th day of February, 1871.

JOSEPH P. ADAMS.
GEORGE HYDE.
